FORMATION TESTER

Lawrence S. Chambers, Los Angeles, Calif.

Application November 12, 1948, Serial No. 59,440

6 Claims. (Cl. 255—1.4)

1

This invention relates to improvements in apparatus for sampling the fluids of earth formations, and particularly underground formations into which bore holes have been drilled.

It has been previously suggested to sample such formations by means of a sampler inserted through the drill pipe of a well and driven into the formation at the bottom of the bore. The sampler comprises a container which is connected to a punch which may be driven into the formation at the bottom of the well. Means are also provided for capturing the sample of fluid, passing through the conduit formed in the punch, in the container.

In constructing and operating such samplers, it has been found difficult to introduce the punch into certain formations, particularly hard formations, without fracturing the formation badly. This permits the drilling mud which is present in the well under high hydrostatic pressure to pass into the formation and into the sampling conduit. Contamination of the sample may result. Indeed, the fracture may be so excessive as to prevent successful sampling of the formation.

In the improvement of my invention, the sampling tube is in the form of a core barrel attached to a sample-receiving container which is lowered through the drill pipe from the surface. By employing a relatively thin-walled coring tube and providing a drilling end to the tube, the tube becomes a rotary core barrel or tube and may be drilled into the formation by rotary drilling methods with little or no fracture thereof. This is because there is but little lateral displacement of the formation. The tube takes the sample through perforations in the wall thereof and around the core in the tube. The sample passes into the sample-receiving compartment to which the coring tube is attached.

In order to minimize the time taken in operating my tool, I employ a sampler which may be introduced into the drill pipe after removing the kelly. The kelly is replaced and the sampler is circulated to bottom. The sampling core barrel tube is passed through the conventional core barrel bit and is drilled into the formation by employing conventional drilling technique.

When the drilling is completed, usually sufficient to advance the drill pipe about one foot, i. e., enough to take about one foot of core in the coring tube, the drilling operation is stopped for a minute or two. During this period the formation is sampled. The sampling of the formation is made under automatically controlled equilib-

2

rium pressure conditions. It is important, in order to obtain a true sample of the formation fluid, that the flow of fluid be at a controlled rate and under controlled pressure. Since the formation fluid (especially if it is petroleum) is a multi-phase fluid including oil, gas, and sometimes water, if the fluid from the formation passes into a receiver at a high rate and at substantially lower pressure than the formation pressure, there will be a phase separation.

In the device of my present invention the formation fluid flows under a balanced pressure and at a controlled rate into a container so that little or no phase separation need occur. The time taken for this sampling need be but a minute or two so that circulation of drilling mud and rotation of the drill pipe are interrupted only for a small period of time. The restriction in the time that circulation or rotation is interrupted is often of vital importance, since, as is well known, in many cases the interruption of circulation and rotation or other movement of the pipe for any protracted period of time is highly dangerous and may result in sticking of the drill pipe due to settling of mud and cuttings in the quiescent column of mud even though highly efficient muds are employed. After the sample is taken the drill pipe is lifted, the pipe set in slips in the rotary table, the kelly is removed, an overshot is lowered into the drill pipe, and the sampler retrieved.

Thus, by employing a coring bit as a sampling tube and an automatic pressure balance during the sampling operation, I can avoid the difficulties which previous devices encountered in sampling formations arising from fracture thereof. A true sample may be taken and all this accomplished in a minimum of time and without the danger of the sticking of the drill pipe. By limiting the time during which circulation or rotation is interrupted sticking of the drill pipe is avoided.

These and other objects of my invention will be apparent to those skilled in the art from the following description taken together with the drawings, in which

Fig. 1 is an assembly view showing the sampler in position in a drill pipe, the drill pipe being shown in section;

Fig. 2 is a section of the lower end of the drill pipe and the sampler with the sampling piston at its initial position, and showing the clock, batteries, and wiring schematically;

Fig. 3 is a view similar to Fig. 2 with the valve 55 pin removed;

Fig. 4 is a portion of the sampler and drill pipe immediately above the sections shown in Fig. 2;

Fig. 5 is a view similar to Fig. 4, corresponding to the condition shown in Fig. 3;

Fig. 6 is a section on line 6—6 of Fig. 5; and Fig. 7 is a top of the section shown in Figs. 4 and 5.

The drill pipe 1 carries a conventional wire line coring bit 2. The sampler 3 is introduced into the drill pipe 1 after removal of the kelly, the drill pipe being suspended in the slips of the rotary table with the core drill suspended above the bottom of the hole. The kelly is replaced and the sampler is circulated to bottom by pumping mud into the drill pipe. Its arrival at the bottom, where it seats on the shoulder of the core bit shown at 12, is signalled by the rise in mud pump pressure.

The sampler is composed of a sampling core tube 4 carrying serrations or teeth 5 on its periphery at its lower end, also perforations 6 disposed throughout the length of the sampling core tube 4. The core tube is screwed into the lower end of conduit 8 positioned in the bottom portion of the sampler. Conduit 3 carries a beveled lower end 9 which forms a conical annulus with the core tube for purposes to be described later, and has a central bore 10. The conduit 8 carries an external shoulder 11 which is seated upon the internal shoulder 12 of the core bit 2.

The conduit 8 is screwed into the tube 13. The tube 13 carries a battery and clock chamber case 14 closed by a top plug 15 and a bottom plug 16 which is screwed into the fitting 11 which is in turn screwed into the internally threaded bore 18 of the conduit 8. The fitting 17 has a side port 19, and a central bore 20 into which is clamped a frangible tube 21 which is sealed at its lower end 22. Positioned within the tube 21 is a cartridge of explosive 23 carrying a cap and insulated electric conductor wires 25 and 26. Wire 26 is grounded at 27, the insulated wire 25 passing through insulating bushing 28 in fitting 17 and through an insulating bushing 29 in the plug 16. Wire 25 is then connected to batteries 30 which are connected by wire 31 to contact arms 33 and 34 of clock 32. Contact 34 is grounded at 35. It will be observed that there is an annular recess 36 which connects the port 19 and the bore 26 to the chamber 37 within tube 13 above the plug 15.

Screwed into the top of tube 13 is plug valve fitting 38 carrying a central check valve 39 containing a downwardly opening port 42, a ball check valve 43 in said port and a spring 41 urging the ball valve downwardly to closed position. Positioned above and communicating with the port 42 is a cross bore 43 carrying a plug 44, a spring 48, a ball check valve 49 to which is connected a pin 50 carrying a bore 51. The top of the plug 38 carries a vertical bore 52 in which a sliding pin 53 is positioned and which passes through the bore 51 to hold the ball check valve 49 from its seat 54. An additional port 55 is also provided in the top of the fitting 38.

The cylinder 56 is screwed onto the fitting 38 and carries a freely sliding piston 57 which makes a seal fit with the walls of cylinder 56. A wire or line 58 is connected to the piston by a swivel 57' and to the pin 53. The cylinder 56 is screwed into the latch fitting 59 carrying at its lower end a bore 60 into which is screwed a choke 61 having a small bore 61' and a conical bore 62 in which is positioned a screen 63. Additional bores 64

are provided in the bottom of the fitting 59 and these bores connect the interior of the cylinder 56 above the piston 57 with the exterior of the sampler and are closed by removable plugs 65.

The fitting 59 has a central bore 66 in which is positioned a flexible, helically wound, coiled tube 67 which is connected by a fitting 68 to the bore 60 at one end and at the other end by a fitting 69 to a bore 82' in tube 70. The tube 70 carries a conical wedge 71 and shoulder 71' which will be described later.

Latches 73 are pivotally positioned upon pivots 74 in slots in the wall of the latch fitting. The upper end of the latch 73 carries a recess 75 in which is seated a coil spring 76 connected at one end to the latch 73 and at its other end to the shoulder 77 depending from the fitting 59. The lower end of the latch is beveled at 78 as indicated for the purpose to be described later.

The tube 70 passes slidably through a bore 79 in the top of fitting 59. The upper end of the tube is connected to a plug 80 inserted in the bottom of the cylinder 81. The tube 70 also carries a central bore 82' which connects the flexible tube 67 and the chamber 82 in the cylinder 81. The top of the cylinder 81 is closed by a plug 83 carrying a bore 84 closed by a plug 85 and also carries an overshot head 86 to which the overshot grapple 87 may be connected as in conventional overshot practice.

To prepare the sampler for insertion into the drill tube, the tube 13 is unscrewed from the fitting 38 and the cylinder 56 unscrewed from the fittings 38 and 59. The piston 57 is pushed down and the pin 53 is fitted into the bore 51 and in the bore 51 of the rod 49, thus pushing the ball check valve from its seat. The ball check valve 39 is on its seat. By withdrawing the piston the line is straightened but not sufficient to withdraw the pin 53 from the bore 51. The tube 56 is then screwed into the fitting 38. The piston is pushed down to its lowermost position. Due to the concave chamber on the underneath side of the piston, the flexible line coils up underneath the piston. The fitting 59, connected to the tube 81 and fitting 83, is screwed into the tube 56. Both of the plugs 65 are removed and water or other liquid is pumped through ports 64 into the tube 56 above the piston. The tube 56 is thus filled with water until it passes out of the other open port 64. The water or other fluid thus stands at a level to submerge the choke 61 with atmospheric pressure in chamber 82. The plugs 65 are then replaced. Plug 15 is removed and the clock set to close contact after a predetermined lapse of time. The plug is replaced, the cylinder 13 screwed into the fitting 38 and the device is thus charged and ready for insertion into the drill pipe after removal of the kelly.

As has been indicated previously, the sampling tube is circulated to bottom with the bit 2 off bottom about two feet. The sampler which passes down through the pipe 1 seats in the position shown in Figs. 1, 2, and 4.

It will be noted that since the frangible tube 21 is closed, the sample-receiving container and all portions of the sampler above the tube are sealed from the mud in the well. The cylinder 81 is positioned on top of the fitting 59 and the wedge 71 is in the position shown in Fig. 4, permitting the spring 76 to push the latches 73 into the recess 88 of the drill pipe underneath the fitting 89 in the drill pipe.

It will be observed that such recesses are con-

ventional in wire line core barrel drills and thus sampler may be employed with an ordinary wire line core barrel. Thus, when it is desired to core as well as sample, wire line core barrel coring may be carried on as is conventional. When it is desired to sample the wire line core barrel may be removed and the sampler introduced in its place. By setting the sample-receiving tube 56 below the latch and the balancing fluid-receiving tube 81 above the latch, it is possible to have a sample-receiving tube of maximum volume, as is permitted by the interval between the latches and the core bit 2 provided by conventional core barrel construction.

The sampler, having reached bottom, is seated on shoulder 12, as is indicated, by a rise in mud pressure, the weight of the drill pipe or that portion thereof as may be desired, as will be directed by good drilling techniques and as will be understood by those skilled in the art, may then be positioned on the latches and the sampling core tube 4. As is conventional, the rotative power is transmitted from the drill pipe 1 to the latches 73 by a shoulder or projection which is positioned in the recess 88, as is conventional in wire line core barrel operations and is not illustrated above. Coring is continued by rotating and advancing the drill pipe. The coring tube 4 is drilled into the formation, a core entering the tube 4. The mud above the core is displaced through the perforation 6 in the portion of the tube core 4. The core tube is drilled into the formation until the bit 2 reaches bottom, as will be signalled by reduction in load on the weight indicator conventionally employed in drilling. The teeth 5 of core tube 4 are offset so as to cut a slight clearance between the core in the tube 4 and the walls thereof and between the tube 4 and the formation. This will permit mud trapped in 4 and 8 above the core in 4 to escape between the core and wall of 4. Drilling is then interrupted.

During drilling operations mud descends through tube 1, around sampler 3, through the annulus 90 surrounding the sampler, and out the port 91 conventionally present in core bits. The mud present in the core tube above the core is displaced by the entering core and acts to lubricate the core tube. As the sampler core tube 4 is drilled into the formation the coring tube 4 enters the formation and the tube 8 is also drilled in, compacting the formation underneath 9 and around the wall 7 to form a seal which seals the outside of the tube 4 in the formation. As is usual, the bottom of the bore is wetted by the mud a couple of inches and is relatively plastic. The wedging action of the bevel 9 compresses this portion of the formation tightly around the tube 4 sealing the clearance which has been cut. The tube 4 is thus sealed in the formation against mud infiltration and against escape of formation fluid around the tube 4. A core is thus drilled and positioned inside the drill sampling tube 4. This core, because of the set of the core teeth on 4, is smaller in diameter than the inside of tube 4.

Formation fluid passes around this core into the chamber 10 and cannot pass further because of the sealing tube 21. Drilling having stopped and circulation interrupted, the clock 32 having been set for a predetermined time, sufficient to permit the above operations to be performed, the clock arm 33 closes contact on 34 and connects the detonating cap in the charge 23 to the batteries 30 and the charge is exploded, fracturing

the tube 21. Communication is now established between the tube 4 and the conduit 20. Formation fluid enters through perforations 6 and passes upward through tube 4, conduit 10, conduit 20, port 19, and the annular recess 92 surrounding the clock chamber 14. Fluid passes into the chamber 37 flowing past the valve 39 lifting the ball check valve 40 off its seat, flowing through the seat 54, entering cylinder 56 underneath the piston 57, lifting the piston.

The rate of ascent of the piston is determined by the rate of passage of fluid from above the piston through the choke 61 and through the conduit 67 into the chamber 82. The pressure on the entering fluid is at all times maintained in equilibrium with formation pressure. This is accomplished by making the choke 61 small, being a needle hole and being replaceable so that the size of the orifice can be adjusted. I can thus maintain the pressure differential above and below the piston relatively low. This piston moves relatively slowly in the cylinder 56 since it cannot move more rapidly than the escape of fluid through the choke. Since the piston moves slowly and fluid from the formation can move no more rapidly than the flow of fluid through the choke and the rate of ascent of the piston, the velocity of the formation fluid entering the sampling chamber is low, resulting in but a small pressure drop due to friction, with little pressure loss for the reason that the fluid entering underneath the piston is substantially at formation pressure. A true sample without phase separation is taken. This sampling is then continued until the piston 57 reaches the top of its travel, at which time it seats against the bottom of the fitting 59 sealing off the chamber underneath the piston 57. The piston, making a fluid-tight seal, maintains the fluid underneath the piston at its formation pressure and prevents both its escape and the contamination by the fluid above the piston. The fluid which is thus discharged through the choke orifice 61 passes up the coil pipe 67 through the tube 82' and into the chamber 82 where it compresses the air in this chamber. When the piston is against the plug fitting 38, the air pressure in 82, above the fluid in 82, is substantially less than formation pressure.

In this position the wire 58 has been extended and the pin 53 withdrawn into the chamber underneath the piston 57. The valve 49 seats, due to the spring action, thus closing off the end of the sampling cylinder and preventing the entry of additional fluid from the bore hole, regardless of higher pressures that may be encountered in the bore hole when the sampling tube is withdrawn from the formation. The pin acts as a trigger which is released by extension of the string. The drill pipe is lifted off bottom, the pipe set in slips, and the kelly removed. The sample may now be withdrawn by introducing the grapple 87 of the overshot, which is lowered on a wire line from the surface until it engages the head 86. Tension placed upon the wire then first elevates the cylinder 81, withdrawing the rod 70, extending the coiled helical tube 67 and engaging the wedge 71 with the beveled portion 78 of the latches 73 and moving the latches into disengaged position shown in Fig. 5. The shoulder 71' on the rod 70 abuts the depending shoulder 77, and further lifting lifts the entire sampler assembly. The sampler containing the fluid sample and the core in tube 4 are returned to the surface.

The sampler is opened by unscrewing cylinder 13 from the fitting 38. The fitting 38 may then be screwed into a container suitable to receive and hold the fluid pressure with suitable provisions for unseating the valve 39. When valve 39 is open a very small pressure within the sample container will unseat ball check valve 49 and permit removal of fluid. Plug 65 may be removed and water or other fluid under pressure pumped into the cylinder 56 above the piston 51 to force the piston down.

While I have described a particular embodiment of my invention for the purpose of illustration, it should be understood that various modifications and adaptations thereof may be made within the spirit of the invention as set forth in the appended claims.

I claim:

1. A formation sampler comprising an upper chamber, a top and bottom closure for said chamber, a tube, one end of said tube connected to said lower closure and to said chamber, a conical wedge on the other end of said tube, a flexible tube connected to said first-mentioned tube, a latch fitting comprising a plurality of hinged links in operative engagement with said wedge, a motion-limiting stop on said first-mentioned tube, a second chamber, the other end of said flexible tube being connected to the top of said second chamber, a freely sliding piston in said second chamber, closable ports connecting the exterior of said second chamber to the top of said chamber, a valve closure at the bottom of said second chamber, said valve comprising a check valve, a trigger in operative association with said valve, a string connected to said trigger and said piston, said string operating said trigger on extension of said string, a sampler core bit connected to said valve, a frangible tube closure separating said core tube from said valve, an explosive charge in said tube, and time-actuated electrical means for exploding said charge mounted in said sampler.

2. A formation sampler comprising an upper chamber, a top and bottom closure for said chamber, a tube, one end of said tube connected to said lower closure and to said chamber, a conical wedge on the other end of said tube, a flexible tube connected to said first-mentioned tube, a latch fitting comprising a plurality of hinged links in operative engagement with said wedge, a motion-limiting stop on said first-mentioned tube, a second chamber, the other end of said flexible tube being connected to the top of said second chamber, a freely sliding piston in said second chamber, closable ports connecting the exterior of said second chamber to the top of said chamber, a valve closure at the bottom of said second chamber, said valve comprising a check valve, a trigger in operative association with said valve, a string connected to said trigger and said piston, said string operating said trigger on extension of said string, a core tube receiving conduit connected to said valve, said conduit having an end having a downwardly beveled end, a core sampling tube connected to said core tube receiving conduit having an external diameter less than the external diameter of said core tube receiving conduit and forming a conical annulus with the end of said core tube receiving conduit, a frangible tube mounted in said core tube receiving conduit and closing said conduit, an explosive charge mounted in said tube, and time-controlled electrical means

for exploding said charge mounted in said sampler.

3. A bore hole formation sampler comprising a housing adapted to be introduced into a bore hole, a fluid sample-receiving chamber in said housing, a travelling piston in said chamber, a sampling tube mounted on said housing and adapted to be fluidly coupled with a formation to be sampled, a fluid channel in said housing for providing a fluid conducting passageway between said sampling tube and said chamber on one side of said piston means normally preventing the entrance of fluid through said sampling tube into said channel, means for disabling said last-mentioned means when said sampling tube is fluidly coupled with a formation to be sampled, whereby fluid from said formation passes through said channel into said chamber and displaces said traveling piston, a normally-open valve in said channel, closing means in said housing for closing said valve, and means coupling said piston and said closing means for effectuating closure of said valve after a predetermined displacement of said piston.

4. A bore hole formation sampler comprising a housing adapted to be introduced in a bore hole, a fluid sample-receiving chamber in said housing, a travelling piston in said chamber, a sampling tube mounted on said housing and adapted to be inserted into the formation to be sampled, a fluid channel in said housing for providing a fluid conducting passageway between said sampling tube and said chamber on one side of said piston, a frangible closure in said channel, means for rupturing said frangible closure when said sampling tube is inserted into a formation whereby fluid from said formation passes through said channel into said chamber and displaces said traveling piston, a normally-open valve in said channel, closing means in said housing for closing said valve, and means coupling said piston and said closing means for effectuating closure of said valve after a predetermined displacement of said piston.

5. A bore hole formation sampler comprising a housing adapted to be introduced in a bore hole, a fluid sample-receiving chamber in said housing, a travelling piston in said chamber, a sampling tube mounted on said housing and adapted to be inserted into the formation to be sampled, a fluid channel in said housing for providing a fluid conducting passageway between said sampling tube and said chamber on one side of said piston, a closure positioned in said channel, means for opening said closure to effect free communication of fluid through said channel into said chamber whereby said traveling piston is displaced, a spring-operated valve means in said channel, retaining means normally retaining said valve means in the open position under tension, and means coupling said retaining means to said piston for releasing said valve means after a predetermined displacement of said piston thereby closing said channel.

6. A bore hole formation sampler comprising a housing adapted to be introduced through drill pipe, a fluid sample-receiving chamber in said housing, a travelling piston in said chamber, a rotary core tube affixed beneath said housing, a fluid channel in said housing providing a fluid conducting passageway between said core tube and said chamber on one side of said piston, a frangible closure in said channel, means for latching said housing in said drill pipe into which

said housing is introduced, whereby said core tube projects beyond the end of said drill pipe, means for rotating said housing and core tube upon the rotation of said drill pipe whereby said core tube is drilled into a formation to be sampled, means for rupturing said frangible closure when said tube is in said formation whereby fluid from said formation passes through said channel into said chamber and displaces said traveling piston, a normally-open valve in said channel, closing means in said housing for closing said valve, means coupling said piston and said closing means for effectuating closure of said valve after a predetermined displacement

of said piston, and means for unlatching said housing from said drill pipe.
